UNITED STATES PATENT OFFICE

EUGENE B. TAGGART, OF INDIANA, PENNSYLVANIA

CLEANING DEVICE

Application filed November 15, 1927. Serial No. 233,419.

This invention relates broadly to the cleaning and separating of materials, and more particularly to an improved apparatus for cleaning coal, ore, and various other materials.

One object of the invention is to provide an improved means whereby the cleaning and separating of materials may be accomplished in a thorough manner and all of the foreign matter removed without the necessity of reworking or subsequent screening or washing.

A further object is to provide a continuous apparatus, in the operation of which the feeding, cleaning and separating occur simultaneously, thus providing for rapid operation in the process, with resultant increase of tonnage per cleaning hour.

Another object is to provide means for cleaning coal in such manner that there is little tendency to breaking up or pulverizing of the coal.

A further object is to provide a means for cleaning and separating, which requires a minimum distance of travel for material operated upon.

With these objects in view, the invention consists, generally stated, in apparatus for moving the material by power and gravitational force in a rectilinear path and subjecting the material while in motion to fluid pressure from beneath, which pressure acts to separate the material and to free it of impurities, the fluid pressure carrying away the lighter impurities such as dust.

In the present invention, in the cleaning of coal, the fluid pressure is of a character to maintain the coal against gravitational force, permitting it to be advanced in its travel during the cleaning operation, while also permitting the heavier particles such as slate to fall beneath the cleaned material.

My invention may be readily understood by reference to the accompanying drawings, which illustrate preferred embodiments of my invention, and wherein

Figure 1 is a side elevation, partly in section, of a cleaning and separating apparatus constructed to carry out the method of my invention; Fig. 2 is an end elevational view of Fig. 1, looking from the right of Fig. 1;

Fig. 3 is a sectional plan view of Fig. 1, showing mainly the feed rollers; Fig. 4 is a transverse sectional view of Fig. 1, taken on the line IV—IV; Fig. 5 shows a modified form of the invention, the view being a transverse sectional view through the apparatus; Fig. 6 is a view similar to Fig. 5 but showing a further modification; Figs. 7 and 8 are plan and longitudinal section views, respectively, mainly diagrammatic, of a further modification; Fig. 9 is a vertical transverse sectional view, corresponding to Fig. 4, of a modification devised especially for cleaning and separating ore; Fig. 10 is a diagrammatic plan view of the separating rolls of Fig. 9, showing one manner of magnetizing the rolls; Fig. 11 is a longitudinal sectional view through apparatus comprising still another modification of the invention; Fig. 12 is an end elevational view, partly in section, taken on the line XII—XII of Fig. 11; Fig. 13 is a transverse section taken on the line XIII—XIII of Fig. 11; and Fig. 14 is a transverse sectional view similar to Fig. 13 of another form of cylinder which may be employed with the form of invention illustrated in Fig. 11.

In accordance with the present invention, and as illustrated more particularly in Figs. 1 to 4, there is shown apparatus for carrying out the method, comprising a pair of inclined rollers 2 suitably journaled in a framing 3. These rollers preferably have their peripheral surfaces formed of brush-like material 4 and the rollers are adapted to lie close together so as to form a mat-like wall of their brush surfaces between the roll bodies. The rollers are shown as driven in unison, in the direction of the arrows in Fig. 4. Suitable gearing indicated generally by the numeral 5 connects the rolls in driving engagement with a motor 6. The rollers may also be driven in directions reverse to those indicated by the arrows, or the direction of rotation of one roller only may be reversed, depending upon the character of material being operated upon and the composition of the rolls. Also, the rollers need not necessarily have brush surfaces.

The framing 3 of the structure may com-

prise side walls 7 which encase the rollers 2, and which extend above the rollers as at 8 to confine the material on the rolls in the cleaning operation. The framing also includes a compartment 9 arranged beneath the rolls and which serves as a bin for catching and retaining the heavier refuse or waste from the cleaning operation.

Located within the bin 9 is a nozzle 10 projecting upwardly towards a point midway between the rolls.

The nozzle is connected to a source of fluid pressure, preferably an air line supplied by a blower or other pressure generating source—not shown. The pressure may also be under control for varying the degree of pressure as needed. Any suitable control may be employed as will be well understood without the necessity of illustration here.

20 The air blast is directed upwardly between the rolls through the mat of bristles which form the brush surfaces of the rolls. When treating damp coal, the air will preferably be heated, to dry it, and facilitate separation.

25 The coal or other material is fed onto the rolls by a chute 11 and after the material has been cleaned, it passes off of the rolls into a chute 12 which directs it to a bin or conveyor, as desired. The rolls are inclined, and

30 may be spaced apart desired distances according to the character and sizes of the material being operated upon. Thus, if the material contains lumps of such shape as to roll readily, the inclination of the rolls will not

35 be so great as in the case of materials which do not tend to roll, while the spacing of the rolls will depend somewhat upon the size of the lumps of slate or the like that have to fall between the rolls.

40 In the operation of the apparatus as above described, the material to be cleaned slides by gravity from chute 11 to the inclined rolls, the rolls, by reason of their inclination, cause the material to advance towards the dis-

45 charge end, and while the material is moving along the rolls it is subjected to fluid pressure from beneath which is directed from the nozzle beneath the rolls through the brush surfaces of the rolls. The material in advancing

50 along the rolls is agitated and stirred thereby, both through the rubbing action of the brush surfaces of the rolls and by their rotary motion, the material tending to bunch at a point between the rolls creates a tumbling

55 and mixing action in the mass and in the cleaning of coal the fluid pressure is maintained at such degree that it will support the coal against falling while at the same time permitting the heavier slate to pass be-

60 tween the rolls into the refuse bin, the lighter particles of the cleaned mass being carried upwardly by the fluid pressure to a suction hood 20 from whence it may be conducted to a waste receptacle (not shown) or recovered.

65 The coal and the slate tend to stratify, with

the slate in closer contact with the rolls, so that the rolls exert a positive force that supplements the gravitational force in feeding the slate downwardly.

The rolls, when rotated in the directions 70 of the arrows of Fig. 4, serve to keep advancing the mixed material into the rising column of air, thus assisting the air in preventing the coal from falling between the rolls; or in other words, hindering the "settling" of the coal.

The apparatus as above described may also be employed in the separation and cleaning of ore. By reason of the difference in the specific gravities of coal and ore, the reverse 80 order in disposition of the worked material will take place, the heavy ore falling by gravity to the bin 9, and the lighter refuse passing off at the discharge end of the rolls.

In Fig. 5 there is shown a modified form of 85 structure for practising the invention, in which only one roll is employed, the principle of operation being the same as in the former structure. The roll 2^a rotates in the direction of the arrow and the material passes along the roll between the roll and a side wall 8^a and is operated on by fluid pressure from a nozzle 10^a.

In Fig. 6, a further modification is shown 90 in which the feed means for agitating and advancing the material may be in the form of belts 2^b passing around the rollers 2^c.

In Figs. 7 and 8 there is shown a modified 100 form of the invention in which the mechanical means for advancing the material while in the process of cleaning and separating comprises rollers 15 which may have brush surfaces or be otherwise formed to give support to the material while permitting the fluid pressure to enter into the mass while being operated upon by the rolls. The rolls 15, in this instance, are arranged with their axes transverse to or at right angles to the direction in which the material is advanced.

By arranging the rolls in this manner, there 110 is provided a positive feeding action for advancing the material, by which the mass of material is worked upon in such manner as to cause stirring thereof or mixing in addition to the action of the fluid pressure to disrupt the mass. The rollers all turn a counter-clockwise direction and it will be seen that as one roll tends to draw the material down, the adjacent roll tends to carry it up, thereby

115 producing a rolling-like movement of the material at the points between the rolls and disrupting or stirring the mass at the zones of fluid pressure between the rolls. With this arrangement of rolls, it will also be seen that as the material which is supported against

120 falling passes beyond the zone of direct pressure it is carried into position between the next set of rolls. In the various stages following beginning of the movement across the rolls, the cleaned material is worked up

125

130

out of the mass and advanced to the discharge position with a minimum of breakage. When the material is passing over the rolls at their highest points, it is not subjected to 5 the agitation that it receives when passing across the spaces between the rolls.

In Figs. 9 and 10, there is shown another form of structure wherein the principle of gravity and angular feed of rollers, together 10 with fluid pressure for cleaning and separating may be used.

The form of apparatus shown in these figures is particularly suitable for use in separating a magnetizable material such as certain metallic ores from a non-magnetizable material. The rolls 18 may be positioned and driven in a manner similar to the disclosure of Figs. 1 and 3 and are of magnetizable material, such as soft iron. In Fig. 10, 20 each roll is shown as being magnetized by magnet coils 24 through electrical conductors 19 and 20 and brushes 21 and 22. Insulating material 23 may be provided on the neck of each roll, for a distance one-half the 25 circumference thereof, so that the magnetism of the rolls will be destroyed when such insulated portion moves into contact with the brushes and breaks the circuit.

As the rolls are rotated in the direction 30 indicated by the arrows in Fig. 4 for instance, each will be magnetized when passing through the plane above the horizontally transverse axes of the rolls, thereby attracting the magnetizable portion of the material and exerting a positive feeding force thereon.

The energizing circuit is broken through entry of the insulated portions 23 beneath the brushes, thus effecting demagnetization 40 of the rolls and permitting the mechanically-attracted material to fall.

Fluid pressure for supporting the lighter lumps of material above the rolls is supplied from a source A past a rotary valve B that 45 may be continuously operated as by a motor C, if intermittent or pulsating supply of fluid pressure is desired as hereinafter explained.

In Figs. 11, 12 and 13 a shell or generally cylindrical drum 25 is arranged to rotate on rollers 26 and may be driven by gearing 27.

The cylinder 25 is open at both ends and is inclined, so that as the material is fed into the upper end thereof, such material will gradually work toward the lower end, through rotation of the cylinder. The cylinder is provided with perforations of such size that the heavier material may pass therethrough and fall into the bin located below such rolls. Air or other fluid pressure is simultaneously directed upwardly through an elongated orifice 28 that is located within the bin, in the position shown in Fig. 4. The lighter material will be prevented by the 55 fluid pressure from falling and will gradu-

ally advance to a discharge chute 29 at the lower end of the cylinder. The bottom wall of the discharge chute extends into the cylinder for a short distance so that the heavier material which has not fallen through the 70 orifices will be discharged beneath the bottom of the chute 29 as shown in Fig. 11. As the material approaches the discharge end of the cylinder 25, the lighter portions thereof will of course be superposed upon the 75 heavier portions, so that the lighter portions will slide down the chute, and the heavier portions fall beneath the chute. Fluid pressure orifices may be provided in addition to the orifice 28, as shown in Fig. 13.

In Fig. 14, I have shown a cylindrical shell 30 which may be mounted and driven in the same manner as the shell 25 and which is provided with orifices to permit discharge of fluid pressure therethrough, but which is of slightly modified form, in that instead of being of polygonal form in cross section, it is circular and is provided with perforated plates or baffles 31 that serve to cause a tumbling or rolling movement of the material to 90 a greater degree than the flattened walls of the cylinder 25, thereby more effectively agitating or stirring the material to expose all portions thereof to the action of the air blast.

In case liquid is employed as the fluid pressure medium, it may be desirable under some conditions to apply the pressure intermittently, in order to more effectively expose all portions of the material to the fluid pressure and to overcome any tendency for the 100 materials to stratify. The air pressure could also be applied intermittently, but it would not be so effective as the fluid pressure in agitating the material.

The invention results in the saving of considerable time in the cleaning of coal or other material as with my improved method, the same volume or quantity of coal may be cleaned in half the travel and time required for cleaning by the screening and washing 110 process.

A further advantage arises in the employment of air or other fluid pressure from beneath the mass which insures a better grade of cleaned material without the necessity of 115 washing.

While I have shown and described preferred embodiments of my invention, it will be understood that they are merely illustrative of the invention and that various other changes and modifications may be made therein without departing from the spirit of my invention or the scope of the claims.

I claim as my invention:

1. Apparatus for separating materials of different character, comprising opposed surfaces moving toward one another and downwardly, for exerting force on one of said materials to direct it to a lower plane, and upwardly directed fluid pressure means for 125 130

holding the other material above said plane, the said fluid pressure means being directed between the said opposed surfaces.

2. Apparatus for separating materials of different character, which comprises oppositely moving surfaces for advancing the materials from opposite directions simultaneously to a zone beneath which there is no positive support, and means for directing fluid pressure upwardly between said surfaces and through said zone with sufficient force to prevent the lighter material from falling, but which permits the heavier material to fall.

3. Apparatus for separating materials of different character, comprising oppositely moving surfaces that are simultaneously operable to advance the materials to a zone beneath which there is no positive support, means for directing fluid pressure upwardly between said surfaces and through said zone with sufficient force to prevent the lighter material from falling, but which permits the heavier material to fall, and means for simultaneously advancing the materials in a direction horizontally transverse to the first-named direction of advance.

4. Apparatus for separating materials of different weight, comprising material-receiving surfaces, one of which is movable toward the other and downwardly, for exerting force on one of said materials to direct it to a lower plane, and fluid-pressure means for holding the other material above said plane, the said moving surface being of brush-like form and compressible to permit the passage of larger particles between said surfaces.

5. Apparatus for separating materials of different weight, comprising a pair of inclined rollers serving as material-receiving surfaces and revolvable in opposite directions for the purpose of advancing material toward the space between the same, and means for directing fluid pressure upwardly between the rollers to support the lighter material and to permit the heavier material to be moved downwardly between the rollers.

In testimony whereof I, the said EUGENE B. TAGGART, have hereunto set my hand.

EUGENE B. TAGGART.
